William M. Milne, Jr. INVENTOR
BY
Frank G. Head ATTORNEY

UNITED STATES PATENT OFFICE

WILLIAM M. MILNE, JR., OF BROOKLYN, NEW YORK

VANITY BOX

Application filed October 27, 1928. Serial No. 315,487.

My invention relates to vanity boxes, and especially to new constructions or arrangements thereof by which a substantial quantity of powder is confined in a magazine compartment, and controllably and gradually delivered in small amounts, as used, to another or "distributing" compartment, which is also the puff-compartment.

The two compartments are so arranged in relation to other parts of the case, that when the latter is open for use and held in a natural position, powder is practically automatically supplied to the puff, or distributing, compartment, in the small quantity needed for facial application; but there is no considerable amount of powder at any time in the distributing compartment, and waste by spilling is practically prevented.

The characteristics and advantages of the invention are further sufficiently explained in connection with the following detail description of the accompanying drawings, which show representative embodiments. After considering these examples, skilled persons will understand that many variations may be made without departing from the principles disclosed and I contemplate the employment of any structures that are properly within the scope of the appended claims.

Fig. 1 is a perspective view of a principal part of the invention-structure, called for convenience, a partition, or "distributing plate".

Fig. 2 is a longitudinal section of a vanity box embodying the invention in one form, and including the distributing plate of Fig. 1.

Fig. 3 is a section at 3-3, Fig. 2.

Fig. 4 is a longitudinal section of a box including a modified distributing plate.

Fig. 5 is a longitudinal section (at 5-5, Fig. 6) of a box of modified form, namely one which is oval in plan-outline.

Fig. 6 is a plan of the same.

Fig. 7 is a section at 7-7, Fig. 6.

The box and its principal interior parts may have almost any general shape or "outline", as sufficiently represented by the rectangular form of Figs. 1 to 4, and the rounded or oval form of the other figures.

Referring first to Figs. 1 to 4:

In the particular form shown, the box proper includes a body or bottom section 1, a lid 2 hinged thereto at 3, provided with the usual mirror 2a, and any known or suitable snap-fastener 4.

Within the bottom section is frictionally fitted, or positively secured, a generally dished plate 5, designed to provide the desired form or contour of the interior of the box body, and also to detachably receive the distributing plate 6, shown separately in Fig. 1. For these purposes plate 5 has a bottom 7 resting on the box-bottom, and an inner wall 8 surrounded by a flat peripheral wall 9 which has a down-turned flange 10 fitting within the upper portion of the body wall.

The distributing plate 6 includes a flat, circumferential, upper-wall portion 12 having its margin bent or pressed to provide a peripheral flange 13, and a down-turned, or substantially vertical, flange 14, designed to have a resilient, frictional fit within wall 8 of plate 5, and thus removably retain the distributing plate therein. Plate 6 has at one end a deep, dished portion, constituting the distributing, or puff chamber, defined by side walls 15, end wall 16, bottom 17, and upwardly-sloping wall or partition 18. This partition wall may be continued horizontally to the front of the plate (the end away from the hinge) as at 19, Fig. 4, or when the box is of sufficient length, as shown in Figs. 1 and 2, this forward portion of the plate may be provided with or pressed to form a rouge tray 20, 85 having a hinged cover 21 provided with a "nail notch" 22.

The stated formation of the distributing plate provides in the front portion of the box a chamber or "magazine" 25, large enough to hold a substantial amount of powder, the "level" of which, except when the chamber is nearly empty, is considerably above the bottom of the puff chamber. A narrow slot 26, of moderate length, is provided in the sloping wall 18 at about its line of juncture with bottom wall 17, through which the powder passes in restricted amount to the bottom of the distributing chamber for application to the puff P.

When not in use, the puff lies upon the slot and acts practically as a stopper, preventing excess flow of powder from the magazine. When the box is open and held in the natural position for powder application, as shown in Fig. 2, the user is facing the mirror; and in manipulating the puff she draws it forward and upward on the sloping wall 18, whereby the powder is spread and properly distributed into the puff, and at the same time a small amount flows into the distributing chamber through slot 26, to keep the chamber sufficiently replenished.

Instead of a slot, the powder-passage may consist of a row of small holes, as at 26a, Fig. 4.

Fig. 4 shows that when desired, the distributing plate, 6a, may be hingedly connected to the box body, or to plate 5, as by the hinge 40. The latch device 4 in the forward, vertical wall of the body 1 may also include an in-pressed portion 4a, cooperating with an indentation in the underlying wall of plate 5, to more positively retain the latter in position.

Figs. 5 to 7 show a modification principally with respect to the general shape or contour of the box, which is in this case approximately oval. The mechanical structure is practically the same as Fig. 4, except that the partition or distributing wall 18a has a central depression or shallow channel 30, and upward-sloping side portions 31.

I claim:

1. A vanity box comprising a bottom section having a hinged lid, and a plate in the bottom section, formed to provide therein a powder magazine and a distributing chamber located substantially side by side, the magazine extending vertically substantially above the bottom of the chamber, the plate having an aperture of small dimensions affording communication between lower parts of the magazine and chamber, the plate also having a wall portion sloping upward from the chamber and over the magazine, the plate also having in an upward, forward part thereof an integrally formed rouge-tray.

2. A vanity box comprising a bottom section having a hinged lid, and a plate in the bottom section, formed to provide therein a powder magazine and a distributing chamber located substantially side by side, the magazine extending vertically substantially above the bottom of the chamber, the plate having an aperture of small dimensions affording communication between lower parts of the magazine and chamber, the plate also having a wall portion sloping upward from the chamber and over the magazine, the plate also having in an upward, forward part thereof an integrally formed rouge-tray and a hinged cover therefor.

3. A vanity box comprising a bottom section having a hinged lid, and a plate movably

inserted in the bottom section and formed to provide therein a powder magazine and a distributing chamber located substantially side by side, the magazine extending vertically substantially above the bottom of the chamber, the plate having an aperture of small dimensions affording communication between lower parts of the magazine and chamber, the plate also having a wall portion sloping upward from the chamber and over the magazine, the plate also having in an upward, forward part thereof an integrally formed rouge-tray.

4. A vanity box comprising a bottom section having a hinged lid, and a plate movably inserted in the bottom section and formed to provide a powder magazine and a distributing chamber located substantially side by side, the magazine extending vertically substantially above the bottom of the chamber, the plate having an aperture of small dimensions affording communication between lower parts of the magazine and chamber, the plate also having a wall portion sloping upward from the chamber and over the magazine, the plate also having in an upward, forward part thereof an integrally formed rouge-tray, and a hinged cover therefor.

5. A vanity box comprising an elongated casing, a powder compartment at one end of the casing, a puff compartment at the other end of the casing, the powder and puff compartments lying side-by-side in substantially the same plane, a partition separating the powder compartment from the puff compartment, said partition having an aperture admitting powder from the powder compartment to the bottom of the puff compartment.

6. A vanity box comprising an elongated casing, a powder compartment at one end of the casing, a puff compartment at the other end of the casing, the powder and puff compartments lying side-by-side in substantially the same plane, an inclined partition separating the powder compartment from the puff compartment, the partition extending across the bottom of the box near the middle thereof and extending over a substantial portion of the powder compartment, said partition having an aperture admitting powder from the powder compartment to the bottom of the puff compartment.

In testimony whereof I affix my signature.

WILLIAM M. MILNE, JR. 120
